COMBINED BRIEF AND OVERNIGHT CASE

Samuel H. Lifton, New York, N. Y.

Application April 9, 1946, Serial No. 660,660

1 Claim. (Cl. 190—44)

1

This invention relates to a composite brief case and suit case, and has for its object the provision of a compact and attractive carrying case or bag having a novel compartment arrangement in which a suit may be carried substantially free from wrinkling, together with other compartments for papers and the like, the case being particularly useful as an overnight bag. Another object of the invention is the provision of an article carrying bag having the convenient expandible features of a brief case together with a compartment provided with means for carrying a suit substantially free from wrinkling. Still another object of the invention is the provision of a serviceable article carrying bag structure of the same general type as a brief case provided with a number of compartments including a compartment for carrying a suit or other articles of clothing substantially free from wrinkling, the latter compartment having closure means independent of that for the other compartments, the bag being of simple and durable construction and having a neat and futuristic appearance. Other objects, advantages, and functional and structural features of the invention will be apparent from the following detailed description taken with the aid of the accompanying drawings wherein:

Fig. 1 is a perspective view of one side of the composite brief and suit case according to my invention.

Fig. 2 is a perspective view of the other side of the brief and suit case.

Fig. 3 is a perspective view showing the closure flap in an opened relation to provide access to the garment concealing envelope.

Fig. 4 is a view similar to Fig. 3 illustrating the envelope opened.

Fig. 5 is a vertical and transverse sectional view taken through the mid-section of the case on the line 5—5 of Fig. 2, however, with the closure flaps shown open.

Fig. 6 is a view similar to Fig. 5 showing the case expanded.

Fig. 7 is a plan view of Fig. 6.

Fig. 8 is an enlarged fragmentary view of Fig. 6, however omitting the garment covering envelope.

Fig. 9 shows the relation of a clothes hanger arrangement disposed within the flexible envelope for enclosing the clothing or garment supported on the hanger, the outline of the envelope being shown in dash-dot lines.

Fig. 10 is a plan view showing the garment concealing envelope as it appears when opened, and

2

Fig. 11 is a fragmentary and front view of Fig. 3, however with the envelope removed.

The composite brief and suit case generally denoted 10 is formed with a front panel 11 and a rear panel 12, each of relatively heavy and durable leather. These panels are interconnected preferably by an intervening contractible and expandible leather bellows or gusset 13 comprising a foldable bottom wall 14 and end walls 15, the latter being secured to the side margins of the front and rear panels by lines of stitching 16, Figs. 1 and 2, and to the lower horizontal margins of the panels by stitching 17.

For strengthening purposes the vertical and lower horizontal margins of the panels are provided with metal reinforcing bars 18 appropriately secured to the inside vertical faces between the lines of stitching 16 and 21 and to the lower margins of the panels between the lines of stitching 17 and 20.

A collapsible metal frame generally denoted 22 (Fig. 7) is attached to the upper margins of the panels 11 and 12 and the gusset 13. The frame 22 comprises leather covered yokes 23 and 24 having their arms 25 and 26 pivotally connected by the shanks of rivets 28 carried by the outside frame 24, the frames being adapted to be collapsed or folded for the purpose of closing the case. On closing the case the outer yoke 24 closely but removably receives the inner yoke 23, the medial upper portions 29 of the gusset being free of the yokes 23 and 24 to permit one yoke to nest within the other without interference from the gusset.

Spaced partitions 30 and 31 extend longitudinally of the inner general compartment defined by the side walls provided by the gusset 13 and the spaced panels 11 and 12. These partitions which divide the case into three compartments or pockets 38, 39 and 40 are disposed and secured to outwardly projecting creases or loops 40'.

When the case is closed, ordinarily the three pockets would be collapsed, as shown in Fig. 5. By means of spreaders, the pockets 38 and 39 may be appreciably extended. For this purpose, swingable spreaders 41 and 42 are employed. Each of these spreaders has a relatively stiff body 43 covered by a flexible casing 44. The spreader 41 has its flexible casing 44 secured along one edge thereof to the panel 12 and gusset 13 by the stitching 17 and 20, the spreader thus being swingable along the line of stitching 20. The other spreader 42 is swingably attached by the line of stitching 20' to the lower margin of partition 31 and an associated loop 40'.

The swingable spreaders 41 and 42 are substantially coextensive with the length of the inner compartment formed by the gusset and the panels and are normally held in vertical position by the inwardly bulging portions 47 and 49 of the sides 15 of the gusset 13.

The spreaders 41 and 42 may be swung downwardly to lie at least in part against the expandible bottom wall 14 when it is desired to extend the capacity of the compartments 38 and 39. When the spreaders are swung downwardly, they provide additional reinforcement to the gusset, preventing sagging thereof when heavily loaded, and they also permit the case to stand upright when set down.

Interconnecting the panel 12 and the partition 31 is an inclined closure 50, preferably of leather. Specifically this closure has its lower margin 50' except for its end portions or folds 52 and 53 (Fig. 11) secured by the lines of stitching 51 to the upper margin of the partition 31. However the entire length of the upper margin of the biased closure 50 is secured by the line of stitching 52' traversing the covering 24' of the yoke 24 and the lower part of the keeper carrying swingable flap F (Fig. 8). The end and vertical margins of the closure 50 are secured to the vertical margins of panel 12 by the lines of stitching 16 and 21. By having the end portions 52 and 53 (Figs. 7 and 11) detached from partition 31, they provide folds, permitting the portions of the gusset 13 between the panel 12 and the partition 31 to be distended or contracted as desired. Or in other words, the closure 50 may be said to have relief means to permit the expansion or contraction of compartment 38.

Appreciably interrupting the panel 12 is the relatively large opening 54 adapted to be closed by the swingable flap or closure means 55 integral with panel 12. The flap 55 is spaced from the vertical rows of stitching 16 and 21 securing the panel 12 to the gusset 13 leaving vertical marginal strips 57 and 58 (Fig. 3) merged with the curved marginal areas 59 and 60 of panel 12. These marginal portions are designed to overlie the marginal portions of the relatively thin and light weight flexible envelope or bag 65 and thus provide appropriate means for retaining the envelope in position, particularly before the swingable flap 55 is closed. Attached to the marginal portions 57-60 of panel 12 is a stringer of slide fastener jaws 66. Also attached to the marginal portions of the swingable flap or closure 55 is a stringer of companion slide fastener jaws 67. A slider 62 is utilized to interlock the jaws, thus removably locking the flap 55 to sustain its closing relation to panel 12.

The flexible envelope 65 (Fig. 10) has wings 66 and 67 provided with reinforced binding strips 68 and 69 sewn to the margins thereof, the wings being secured to a body portion or backing 70 by rows of stitching 71 by which a further binding 72 is also attached to the body portion and also about the edges of bottom flap 73 and a top flap 74. The side wings 66 and 67 fold across the body portion 70 substantially along a line defined by the binding 72 and stitching 71. In closing of the envelope, the swingable wings 66 and 67 are first swung inwardly and towards the backing 70. Thereafter the wings are in overlapping relation and are disengageably held together by the companion snap fastener elements 75 and 76. Two female elements 76 are shown and these are employed severally, depending upon the bulk of the garment to be enclosed by the

envelope. The bottom flap 73 is then swung upwardly while the top flap 74 is swung over a portion of the bottom flap 73 to which it may be fastened by a snap fastener member 77 co-operating with any one of the complementary spaced snap fastener members 78 on the bottom flap in accordance with the amount of clothing placed in the envelope.

Sustained by the biased closure 50 is the garment hanger or supporting and retaining means generally designated 80 removably carried by the hook 81 fastened by rivet 82 to the biased flexible closure 50. The hanger may be said to embody complementary hanger members generally indicated 83 and 84. The garment is supported by the hanger member 83 and is retained on the latter by the hanger member 84.

The hanger members 83 and 84 are swingably related or connected and the former is a one piece wire comprising a cross bar 85, vertical sides 86 and the inclined arms 87 each terminating in an eye or bearing 88 loosely and rotatably surrounding the hanger member 84 at horizontal portions 89 of the U shaped or indented portions 90 merged with the horizontal portions 91 integral with the inclined arms 87 common to the bridge or cross bar 85.

Extending inwardly from the U shaped portions 90 are the horizontal limbs 94 merging with inverted U shaped portion or crown 95 adapted to be hooked on and retained by the fixed hook 81 carried by the flexible and biased closure 50.

Normally the garment supporting hanger member 83 is nearest to partition 31 and the retaining hanger member 84 lies against the hanger member 83 although the crown loop 95 of the former projects through opening 96 in the garment concealing envelope 65. More particularly opening 96 is at the upper medial part of the backing or body portion 70 and at the lower medial part of the upper swingable flap 74.

With the crown 95 projecting through opening 96, it may be readily positioned and sustained by the hook 81. Thereafter a garment not shown may be readily placed on the garment supporting hanger member 83 and neatly folded thereabout after which the swingable or hinged retaining hanger member 84 is pivotally dropped onto the folded garment. If desired cross arm 85 may be also utilized to sustain a garment. Subsequently the wings 66 and 67 are swung inwardly and locked, thus holding the retaining hanger member 84 appropriately against the garment. Thereafter the lower and upper flaps 73 and 74 are swung against the locked wings and interlocked. By the arrangement disclosed, the garment is neatly confined in the envelope which in fact is sustained by the limbs or shoulders 91 of the retaining hanger member 84. Thus the envelope 65 is removably supported by the hanger arrangement 80 although the latter is removably carried by the hook 81 or in other words by the biased closure 50.

With the envelope closed it is positioned within the compartment 38, thus expanding the latter to compensate for the added bulk of the folded garment although at this time the margins 57-60 cooperate with the envelope to preclude accidental withdrawal thereof through the opening 64 bounded by the fastening jaws 66. Subsequently the closure 55 which is an integral part of the front panel 12 is raised to fully conceal the envelope and the rider 62 is utilized to close the slide fastener jaws.

Compartment 38 may be expanded if required

by the use of the swingable drop bottom member 41. The same holds true for compartment 39 in the utilization of the swingable spreader 42 and the case 10 may be fully closed by flap F carrying a lug or keeper K locked by suitable latching means L and when the case is closed, handle H may be conveniently grasped to carry the case about as is well understood.

Various changes may be made in the construction and arrangement of parts without departing from the spirit of the invention or sacrificing any of the advantages thereof inherent therein.

I claim:

In a carrying case wherein an envelope removably surrounds an article and is provided with a gap at a medial portion thereof and wherein hanger means in part projects through said gap and in part is removably disposed within said envelope for sustaining said article, an outside flexible panel, an inside wall spaced from said panel, expandible and contractible gusset means interconnecting said wall and panel and defining therewith a compartment to receive said envelope, said panel having spaced and vertically disposed marginal strips and upper and lower horizontally arranged marginal portions, said panel having spaced corner sections having lower curved margins merged with said upper marginal portion and with the upper parts of said strips; said upper and lower marginal portions, strips and curved margins defining a marginal rim having a relatively large opening with said vertically disposed strips being spaced apart a distance less than the length of said envelope, a flexible cover substantially complementary to said opening to provide access to said compartment and to said envelope therein and integral with said lower marginal portion and removably interposed between said strips and upper marginal portion, disconnectible

fastening means secured to said strips and to said upper marginal portion and to the side and upper marginal parts of said cover, said marginal strips and said sections cooperating with side marginal portions of said envelope to retain the latter in said compartment even though said cover is swung downwardly and outwardly and about said lower marginal portion, flexible means bridging the top of said compartment and secured to said panel and wall, and holding means carried by said flexible means for removably supporting said hanger, said strips and marginal portions cooperating with said holding means to retain said envelope within said compartment.

15 SAMUEL H. LIFTON.
